UNITED STATES PATENT OFFICE.

CHRISTIAN HAMILTON GRAY, OF ESSEX, ENGLAND.

PRESS FOR VULCANIZING-MOLDS.

1,234,330.

Specification of Letters Patent. Patented July 24, 1917.

Application filed November 7, 1916. Serial No. 129,949.

To all whom it may concern:

Be it known that I, CHRISTIAN HAMILTON GRAY, a subject of the King of England, residing in Essex, England, have invented 5 certain new and useful Improvements in Presses for Vulcanizing-Molds, of which the following is a specification.

This invention is for improvements in or relating to presses for vulcanizing-molds, 10 and has for its object to provide a press which cannot be operated to put such pressure on the molds as to either damage them or itself.

According to the present invention, a 15 press for vulcanizing molds is characterized by the press-plate being supported above the bed upon guiding members constructed to engage with the plate to exert an upward thrust thereon but to be movable downward relatively to the plate without exerting a downward thrust thereon, and power-driven mechanism to raise the plate by means of the said members and permit it to descend under the action of gravity alone.

20 It has before been proposed to raise and lower a top-plate of a vulcanizing-mold by means which cannot exert downward pressure upon it, but in use this plate was intended to be locked in position prior to applying pressure by a specially constructed ram.

It has also been proposed to force down the ram of an electrical press by a lever having one end connected to a nut engaged 25 by a spring-controlled screw-threaded spindle, so that the ram would be positively lowered and forced down by the operation of the screw-threaded spindle until the pressure of the controlling spring was overcome, 40 when the spindle would adyance against the spring, the nut and ram meanwhile remaining stationary, and in its movement operate a switch to cut off the driving current. It will be seen that neither of these proposals anticipates the employment of the 45 dead weight of a press-plate to apply the required pressure.

In the accompanying drawings which illustrate one method of carrying out this 50 invention—

Figure 1 is a vertical section through the press showing a few molds in position;

Fig. 2 is a plan of an end-portion of the press, and

Fig. 3 is a horizontal section through a portion of one of the plates of the press.

The same letters indicate the same parts throughout the drawings.

The bottom plate A of the press is a fixture being carried on supports A¹. The upper plate A² has guide-lugs A³ secured one at each end. Each of these lugs has a square hole which takes a nut B whose exterior is square to fit the lug loosely and whose interior is screw-threaded to engage 65 the thread of a vertical lifting-spindle B¹. The bottom of each nut is flanged at B² to engage the under-face of the lug A³. The spindles B¹ are geared by miter gearing to a driving-shaft C which receives motion 70 from an electric motor D through pulleys D¹ and C¹ and a driving-belt C². The motor is controlled by a bell-crank lever E pivoted at E¹ and connected by a link E² to a switch-arm E³ on the motor. Pivoted 75 to the lever E at F¹ is a vertical rod F which slides in bearings indicated in dotted-lines at F². Fixed to the rod are stops F³, F⁴ respectively which coöperate with a tongue A⁴ on the left-hand lug A³ of the 80 top plate of the press.

The operation of this apparatus is as follows:—

To raise the top plate of the press, the lever E is pulled down so that the switch-arm E³ will be thrown over to the "up" position indicated on the motor D, and with this movement of the lever E, the vertical rod F will be drawn down so that the stop F⁴ is brought nearer to the tongue A⁴ on the lug A³ of the press-plate A². The motor being started by the movement of the switch-arm E³, operates the shaft C and thus drives the spindles B¹ through the miter-gearing by which they are connected to the said shaft, and in this manner the nuts B are made to travel up the spindles B¹. As they advance, they pick up the plate A² by means of the flanges B² which lie under the lugs A³ and raise the plate free 100 of the molds in the press, which molds are indicated at G. As soon as the plate is free of the molds, the tongue A⁴ on the lug A³ strikes the stop F⁴ and raises the rod F, so that by this means the lever E is 105 raised, and thus the switch-arm E³ of the motor is brought over to the "stop" position, whereupon the motor stops and the

plate A² is held in the position to which it has been raised.

To return the plate A² the lever E is raised and thus the switch-arm E³ is brought over to the "down" position on the motor D. This reverses the motor so that the operation of the parts is reversed and the plate A² is lowered until it rests on the molds G. By this time the tongue A⁴ has come into contact with the stop F³ and has thus moved the switch-arm E³ of the motor D over to the "stop" position. The motor does not immediately stop so that the nuts B still continue to travel down slightly, but this has no effect upon the plate A² as the nuts B are free in the lugs A³ and thus the plate A² only lies on the molds with its own weight.

It will thus be seen that in no circumstances can greater pressure be put upon the plate A² than is due to its own weight, and this plate is made sufficiently strong to support itself without damage. The weight of the plate is made sufficiently great to put the required pressure upon all the molds when the press is full, all molds put in at one time being made of equal thickness.

The construction of the plates is the same as that commonly employed for steam-heated press-plates, the whole interior A⁵ being provided with a series of baffles A⁶ which provide a sinuous course for the steam and also serve as ties between the top and bottom walls of each hollow plate. The upper plate may be lagged, as indicated at A⁷, and the lagging may extend down in the form of a hood over the sides of the bottom plate, as indicated at A^{7*}, though at the ends where this downward extension is shown, a slot is necessarily provided in the lagging for the lugs A³.

Should the automatic mechanism for stopping the motor become deranged at any time, no harm will accrue to the press, as the spindles B¹ are provided with plain extensions B^{1*} which would receive the nuts B so that the plate would not be thrown

from the spindles but would merely rest at the top of the same while the spindles continued to rotate.

Obviously other means may be employed for raising and lowering the plate A² according to this invention, for example, instead of the nuts B, the plate could be lowered by chains or other flexible means which cannot exert any downward thrust upon the plate, so that when brought down upon the molds, a thrust equal to its own weight only, would be exerted upon the latter. Further, where it is preferred to make the plate itself lighter than will give the required pressure, weights may be placed upon it to the required amount, the object being never to allow the pressure to exceed the predetermined maximum value.

What I claim as my invention and desire to secure by Letters Patent is:—

1. In a press for vulcanizing molds, the combination of a bed, a press-plate supported above the bed upon guide members constructed to engage the plate to exert an upward thrust thereon but to be movable downward relatively to the plate without exerting a downward thrust thereon, and power-driven mechanism to raise the plate by means of said members and permit it to descend under the action of gravity alone, substantially as described.

2. In a press for vulcanizing-molds, the combination of a bed, a press-plate supported above the bed upon guide-members constructed to engage with the plate to exert an upward thrust thereon but to be movable downward relatively to the plate without exerting a downward thrust thereon, and power driven mechanism provided with automatic stop-gear controlled by the position of said plate relatively to the bed to raise the plate by means of the said members and permit it to descend under the action of gravity alone, substantially as set forth.

In testimony whereof I have signed my name to this specification.

CHRISTIAN HAMILTON GRAY.
